US0D1043801S

(12) **United States Design Patent** (10) Patent No.: **US D1,043,801 S**
(45) Date of Patent: ** Sep. 24, 2024

(54) **SPECTACLES**

(71) Applicant: **BALENCIAGA**, Paris (FR)

(72) Inventor: **Demna Gvasalia**, Paris (FR)

(**) Term: **15 Years**

(21) Appl. No.: **35/518,286**

(22) Filed: **Aug. 24, 2023**

(80) **Hague Agreement Data**

Int. Filing Date: **Aug. 24, 2023**

Int. Reg. No.: **DM/231129**

Int. Reg. Date: **Aug. 24, 2023**

Int. Reg. Pub. Date: **Sep. 8, 2023**

(30) **Foreign Application Priority Data**

Mar. 4, 2023 (EM) 015013450-0001

(51) **LOC (14) Cl.** **16-06**

(52) **U.S. Cl.**

USPC **D16/314**

(58) **Field of Classification Search**

USPC D16/300, 306, 313–315, 320, 321, 326,
